UNITED STATES PATENT OFFICE.

FREDERICK JOHN CHOLES, OF PIETERMARITZBURG, NATAL.

SIGHT FOR FIREARMS.

SPECIFICATION forming part of Letters Patent No. 691,242, dated January 14, 1902.

Application filed September 28, 1901. Serial No. 76,907. (No model.)

To all whom it may concern:

Be it known that I, FREDERICK JOHN CHOLES, captain, ordnance officer, a subject of the King of Great Britain and Ireland, residing at Pietermaritzburg, in the Colony of Natal, have invented certain new and useful Improvements in or Connected with Sights for Rifles, Machine-Guns, and other Firearms; and I do hereby declare the following to be a full, clear, and exact description of the invention, such as will enable others skilled in the art to which it appertains to make and use the same.

The object of my invention is to provide a back-sight arrangement for rifles, machine-guns, and other firearms by which defects in the sighting thereof can be readily remedied with ease, expedition, and accuracy and which will constitute an efficient wind-gage and obviate the necessity for the use of detached sighting appliances.

I will describe my invention with reference to the accompanying drawings, in which—

Figure 1 is a plan with the sight-leaf lowered, and Fig. 2 an elevation with the sight-leaf raised, of a sighting arrangement according to my invention. Fig. 3 shows a modification of the screw.

Secured to the barrel A is the base A² of the back-sight arrangement. The leaf-bed B is pivoted at b to the base A² and is provided with a dovetail projection b², which works in a corresponding groove in the base A².

C is the sight-leaf, hinged to the leaf-bed B and carrying the back sight c, the said bed B having in it a curved slot c², the curve being struck from the center b. A pinching-screw D (provided with a handle d) passes through this slot and is screwed into the base A². On the rear end of the bed B are teeth c³, with which engages a worm e on a shaft E, mounted in fixed bearings e² and provided with a milled head e³, so that by operating this the leaf-bed B can be moved in either direction sidewise on the center b, carrying with it the back-sight leaf and back sight, so as to counteract any defect in the alinement of the back sight and fore sight and to make allowance for windage as required. When the adjustment is made, the leaf-bed B can be fixed by the pinching-screw D.

If desired, the screw D can be replaced by

a pointer D'. (Shown in Fig. 3.) A scale is marked at the edge of the slot c² to indicate the required adjustment for windage.

55

Figs. 4 and 5 are views similar to Figs. 1 and 2, showing another mode of mounting the leaf-bed B on the base A², the pivot b, on which the leaf-bed is capable of being adjusted laterally, being in this modification situated about midway between the ends of the leaf-bed, the said leaf-bed having on its under side two curved grooves a, engaging with projections b² in the base A², struck from the center of the pivot b. The projections b² and the curved grooves 65 a may be dovetail or other suitable shape to retain the leaf-bed in contact with the base A².

60

It is obvious that in both modifications the projections b² and the grooves a may be reversed—that is to say, the curved grooves may 70 be in the under side of the leaf-bed B and the projections b² on the base A², as shown in Figs. 4 and 5.

I claim as my invention—

1. An improved sight for rifles and the like, 75 comprising a base on the rifle-barrel, a leaf-base pivoted thereto, the base and leaf-base being provided with curved engaging projections and grooves concentric with the pivot, substantially as described.

80

2. An improved sight for rifles and the like comprising a base secured to the barrel, a leaf-base pivoted thereto, the base and leaf-base being provided with curved grooves and projections concentric with the pivot, in combination with gearing to move said leaf-base and a means to lock the leaf-base in its adjusted position, substantially as described.

85

3. An improved sight for rifles and the like, comprising a base secured to the barrel, a leaf-base pivoted thereto and carrying a hinged sight-leaf, the base and leaf-base having curved dovetailed grooves and projections between the base and leaf-base concentric with the pivot and means for moving the leaf-base radially on its pivot, substantially as described.

90

In testimony whereof I affix my signature in presence of two witnesses.

FREDERICK JOHN CHOLES.

Witnesses:

WILLIAM JOHN WEEKS,
GEORGE CLARKE HAWKES.
